COATING PROCESS AND APPARATUS

Edward S. Killian, Akron, Ohio, assignor to Frank B. Killian & Company, Akron, Ohio, a partnership

Application July 30, 1947, Serial No. 764,717

10 Claims. (Cl. 18—24)

1

The present invention relates generally to the art of forming articles from liquids, and is particularly concerned with a novel method of making thin rubber articles, and with novel apparatus implementing that method.

It has heretofore been customary in making balloons, finger cots, gloves, nipples and similar articles of rubber, to immerse a form in liquid latex and then to lift the form from the latex and cause the film adhering to the form to dry and solidify. It has been found that circulation of the liquid latex is important to the production of satisfactory latex films, especially if the dipping operation is carried out over an extended period and involves repeated dipping of forms into the liquid latex, in accordance with present commercial manufacturing operations. The forms inhibit rather than promote such circulation of liquid latex and, as a result, films formed on the forms often contain air bubbles and other weakening defects which may render the resulting articles worthless, or at least materially reduce their value and usefulness. Furthermore, the temperature of the liquid latex, which is rather critical within a certain range of temperatures, so far as the character of the articles produced is concerned, is difficult to control in conventional practice due to the repeated immersion of forms which ordinarily have a temperature substantially higher than the maximum desirable latex temperature.

By virtue of the present invention, which is predicated upon my discovery that it is not necessary to completely immerse a form to produce satisfactory latex films and rubber articles, the difficulties aforementioned may for the first time be overcome. In addition, the present invention enables much more rapid production of thin rubber articles than has ever heretofore been possible.

Briefly stated, the method of my invention includes the steps of moving sideways a substantially horizontally disposed revolving form, and flowing a dipping bath lengthwise of the form from its supported end to its free end and in contact with the lower part of the form.

In carrying out this method to produce a rubber prophylactic, I have disposed a suitable form at a small angle to a dipping bath of liquid latex so that the lower part of the free end of the form is immersed in the liquid, and so that the lower part of the body of the form is in contact with the liquid to the extent necessary to produce an article of the length desired. The opposite end of the form is supported and the form is simul-

2

taneously rotated and moved sideways while the form is in contact with the bath. The liquid latex is caused to flow substantially horizontally in a direction substantially at right angles to the sideways movement of the form and along the form from the supported portion to the free end thereof. Under these circumstances the form has the effect of dampening any wave motion in the bath, and the tendency for uneven deposition of, or bubble inclusions in, latex upon the form is substantially overcome because the resistance to liquid latex flow by the form is substantially at a minimum. The manner in which the form is disposed with respect to the bath and the manner in which the bath is circulated with respect to the form are responsible for the success of the method of my invention in producing thin rubber articles of superior grade and uniformity.

Instead of moving the forms sideways, they may be moved in the direction of their longitudinal axes and substantially the same results will be obtained. In other words, assuming the same bath circulating circumstances and the same disposition of the forms with respect to the bath, no appreciable defects in the resulting products will result from moving the forms in the same direction as the flow of the portion of the bath in contact with the forms, provided that the relative movement of the bath and forms is not too great. Similarly, the forms may be moved at an angle between these two extremes, that is, between purely sideways movement and axial movement.

In the practice of this method, I have found it desirable to expose the upper portions of the forms in contact with liquid latex to drying circumstances. In this manner, by regulating the rate of rotation of the forms I have been able to produce exceptionally strong and durable rubber articles due, I believe, to the fact that instead of

a single film such as is obtained in conventional dipping practice, my articles are formed of a plurality of individual films securely bonded together. As the form is rotated so that said lower portion gradually becomes the upper portion and contacts the atmosphere under drying conditions, the film of latex adhering to said lower portion of form is dried or partially dried, and as the form rotates further that film is immersed in the latex and carried through the cycle, with the result that a second film is deposited on the first film and dried or partially dried prior to the deposition of still another film.

By adjusting the length of the period of contact of the form with the dipping bath through regulation of the rate of travel and rotation of

the form while in contact with the bath, I can produce rubber articles of wide variety of weights and thicknesses. These articles, regardless of their weights or dimensions, are of greater strength and durability and uniformity than similar articles heretofore produced by conventional methods.

If desired, the forms may be regulated and rotated after the manner described and claimed in United States Patent No. 2,128,827 to maintain uniformity of films deposited on the forms. Also, the forms may be passed through the successive stages described in that patent to thoroughly process and finish the films.

The novel apparatus of this invention, by means of which I have successfully carried out the foregoing method, will be better understood by those skilled in the art upon referring to the drawings accompanying and forming a part of this specification in which:

Figure 1 is a side view partly in section of one form of apparatus of this invention with certain parts removed;

Figure 2 is a plan view of the apparatus of Fig. 1;

Figure 3 is an end elevational view of the form rotating means of the apparatus of Figs. 1 and 2; and,

Figure 4 is a plan view in section of one of the forms illustrated in Figs. 1 and 2.

In general, the apparatus of this invention includes a receptacle R, a liquid latex bath B in the receptacle, means M for circulating the bath, dipping forms F, and means S for moving the forms sideways and simultaneously rotating the forms.

The illustrated receptacle R is an open top metal tank having a bottom wall 10, side walls 11, an end wall 12, and another end wall 13 which defines a substantially circular chamber 14 having an open top and side portion. The receptacle R is provided with a false bottom 15 comprising a metal plate secured to the side walls 11 between the ends of the receptacle by braces 16. The false bottom 15 divides the receptacle into substantially equal upper and lower sections and defines with the end wall 12 a passage for liquid between the upper and lower sections. In the portion of the false bottom within chamber 14 and adjacent to wall 12, an aperture 17 is provided to permit liquid to flow between the upper and lower sections.

The end 12 of the receptacle includes a flange 20 extending away from the receptacle and upwardly at an angle of about five degrees. A synthetic rubber strip 21 is secured along the upper part of wall 12 and within the receptacle to define with wall 12 a continuous curved surface. The upper edge of strip 12 is disposed above the normal level of latex in the receptacle and serves as a resilient bumper or bearing edge for the forms F when they move too far downwardly into the bath B.

Means M comprises a paddle wheel having a shaft 25 which is engaged for rotation with suitable means (not shown), such as an electric motor. The shaft 25 is disposed substantially vertically and the paddle wheel is disposed within the chamber and below the false bottom 15. The paddle wheel is a conventional type and includes a center section 26, a plurality of arms 27 extending outwardly therefrom, and buckets or blades 28 secured to the outer ends of said arms.

The forms F are elongated, hollow, cylindrical glass elements having closed, rounded ends and

open ends. The forms are disposed to roll on a rubber track 30 secured to the upper surface of flange 25 in such a manner that the lower sides of the form will dip into the liquid latex L. The forms are disposed with their longitudinal axes substantially parallel to the upper surface of flange 25 and, therefore, at an angle approximating 5 degrees to the surface of the liquid latex L. The forms are maintained in this position with respect to the track 25 by means S, the open end portion of each form being gripped between the track 30 and means S.

Means S includes a revolving belt 35 to roll forms F on the track 25, a second revolving belt 36 to which the forms are attached, a plurality of springs 37 bearing against the belt, a plate 38 retaining the springs in position relative to the form, driving pulleys 39 around which the belt is disposed, and mechanism such as electric motors (not shown) for driving the pulleys and belts 35 and 36. The forms are secured to the belt 36 in such manner as to be rotatable relative to said belt.

As will be apparent from the drawings, a plurality of forms F may be arranged with their longitudinal axes substantially parallel and with adjoining forms spaced close together. The belt 36 may be arranged to carry the forms through a plurality of stations along a closed path including receptacle R, as disclosed in aforementioned United States Patent No. 2,128,827. The track 30 may extend beyond the ends of the receptacle to support the forms in their course of travel between and through the various stations, and the portions of the track adjacent to the receptacle are disposed to carry the forms upward and over the side walls of the receptacle.

In the operation of the illustrated apparatus, with the paddle disposed in position in the chamber 14 and shaft 25 extending vertically upward from the wheel and operatively engaging paddle driving means, liquid latex L is introduced into receptacle R until the receptacle is substantially filled. A plurality of forms F are disposed as illustrated upon track 30 in engagement with the unsecured upper end strip 21 and rotatably attached to belt 36. The forms engaging the strip 21 are gripped between track 30 and belt 35. In this position the forms engaging strip 21 are disposed with their lower portions in contact with the liquid latex L so that the closed ends of the forms are approximately half immersed in said liquid latex, and so that the length of the desired articles is equal to the length of the portion of the forms F in contact with the liquid latex. The forms are rotated by means S and the paddle wheel is rotated, causing circulation of the liquid latex in a substantially horizontal direction toward end 12 of the receptacle but beneath false bottom 15. The liquid latex flows upwardly through the opening between the end 12 and the false bottom 15 and in contact first with the mid-section of the rotating forms F, and thence along the forms, finally flowing in contact with the submerged closed end portion of the forms. Completing its circulation cycle, the liquid latex flows into chamber 14, downwardly through the openings 17 and into contact with the buckets 28 of the paddle wheel. The form is simultaneously moved horizontally and rotated relative to the surface of the liquid latex by means S. When the desired film has been developed upon the forms, the forms are lifted from contact with the liquid latex and moved along the path of belt 36 to another station for further

processing. As one form is removed from the bath, another is introduced, making the operation a continuous one. In known manner, the forms may be cured or partly cured on the forms at various stations along the path of belt 36, and the forms may be cleaned and washed and dried in preparation for a subsequent dipping operation in a repetition of the cycle.

Although I have specifically described only one form of this invention, I contemplate other forms which, as a matter of routine, will occur to those skilled in the art. For instance, instead of the strip 21 being disposed as shown and normally out of contact with the forms F, said strip might be disposed to constantly bear against and support forms F as they pass along the receptacle in contact with the dipping bath. I consider such other forms as within the spirit of this invention and within the scope of the appended claims.

Having thus described the present invention so that those skilled in the art may be able to understand and practice the same, I state that what I desire to secure by Letters Patent is defined in what is claimed.

What is claimed is:

1. The method of making a dipped article which comprises the steps of moving sideways a substantially horizontally disposed revolving form supported at one end, and moving a film forming liquid lengthwise of the form toward its free end while maintaining the form in substantially horizontal position.

2. The method of making a thin rubber article which comprises the steps of moving sideways a substantially horizontally disposed revolving form supported at one end, and moving liquid latex lengthwise of the form toward its free end while maintaining the form in substantially horizontal position.

3. The method of making a thin rubber article which comprises the steps of moving sideways a substantially horizontally disposed revolving form supported at one end, moving liquid latex lengthwise of the form toward its free end while maintaining the form in substantially horizontal position and subjecting latex film deposited on said form to drying conditions.

4. Apparatus for making deposited articles comprising a receptacle for film forming liquid, an elongated form disposed substantially horizontally with its under portion partially immersed in said liquid, means for moving said form substantially horizontally across the receptacle while so disposed, means for rotating said form while so moving, and mechanical means in the liquid for moving said liquid lengthwise of said form toward its free end while the form is being so moved and rotated.

5. Apparatus for making thin rubber articles comprising a receptacle for liquid latex, a cylindrical form supported near one end and maintained at a slight angle to the surface of said liquid latex with its under portion and free end partially immersed in said liquid latex, means for moving said form substantially sideways across the receptacle while so positioned, means for rotating said form while so moving, and mechanical means in the latex for moving said latex lengthwise of said form towards its free end while the form is being so moved and rotated.

6. Apparatus for making thin rubber articles comprising a receptacle for liquid latex, a cylindrical form supported near one end and maintained at a slight angle to the surface of said liquid latex with its under portion and free end partially immersed in said liquid latex, means for moving said form substantially sideways across the receptacle while so positioned, means for rotating said form while so moving, and mechanical means including a paddle wheel in the latex for moving said latex lengthwise of said form toward its free end while the form is being so moved and rotated.

7. The method of making a thin rubber article which comprises the steps of moving sideways a substantially horizontally disposed revolving form supported at one end, contacting the form with a liquid latex dipping bath, holding a part of the free end of the form above the surface of said bath throughout the period that the form and bath are in contact, and moving the bath lengthwise of the form and toward its free end.

8. Apparatus for making thin rubber articles comprising a receptacle for liquid latex, a cylindrical form supported near one end and maintained at a slight angle to the surface of said liquid latex with a part of its free end above said surface and another part of said end immersed in the liquid latex, means for moving said form substantially sideways across the receptacle while so positioned, means for rotating said form while so moving, and mechanical means in the latex for moving said latex lengthwise of said form toward its free end while the form is being so moved and rotated.

9. The method of making a dipped article which comprises the steps of moving sideways a form supported at one end and comprising an elongated cylindrical portion and a semi-spherical free end portion, contacting only the lower part of said semi-spherical end and the under side of the said cylindrical portion of the form for the length of the desired article with a film-forming liquid, and rotating said form while maintaining said limited contact with the liquid.

10. The method of making a dipped article which comprises the steps of moving sideways a form supported at one end and comprising an elongated cylindrical portion and a semi-spherical free end portion, contacting only the lower part of said semi-spherical end and the under side of the said cylindrical portion of the form for the length of the desired article with a film-forming liquid, rotating said form while maintaining said limited contact with the liquid, and flowing the liquid along the forms from their supported ends to their free ends while they are being moved sideways and rotated as specified.
